CLAIM

The ornamental design for a tail light for automobile as shown and described.

DESCRIPTION

FIG. 1 is a front elevational view of a tail light for automobile of our new design;

FIG. 2 is a rear elevational view thereof;

FIG. 3 is an enlarged left side elevational view thereof;

FIG. 4 is an enlarged right side elevational view thereof;

FIG. 5 is a top plan view thereof;

FIG. 6 is a bottom plan view thereof;

FIG. 7 is a top, front, and right side perspective view thereof; and,

FIG. 8 is a top, front, and left side perspective view thereof. The broken lines illustrate a portion of the tail light for automobile that form no part of the claimed design. The portion of the drawings shown in a lighter tonal value within the broken-line perimeter illustrates a portion of the tail light for automobile that forms no part of the claimed design.

1 Claim, 8 Drawing Sheets
